Term of patent 14 years

(Cl. D90—20)

Fig. 1

FIG. 2

FIG. 3

FIG. 1 is a perspective view of a tire showing the new design, it being understood that the tread portion is repeated throughout the circumference of the tire and that the opposite side of the tire is conventional;

FIG. 2 is an enlarged fragmentary plan view of the tread portion of the tire shown in FIG. 1; and

FIG. 3 is a fragmentary transverse sectional view through the tire substantially on the plane indicated by the line 3—3 of FIG. 2.

I claim:

The ornamental design for a tire, substantially as shown and described.
